UNITED STATES PATENT OFFICE

SOLOMON KARPEN, OF CHICAGO, ILLINOIS, ASSIGNOR TO S. KARPEN & BROS., OF CHICAGO, ILLINOIS, A CORPORATION OF WEST VIRGINIA

SOFA-BED

Application filed March 18, 1931. Serial No. 523,533.

This invention relates particularly to an improvement in sofa-beds of the class employing a folding portion capable of occupying a vertical position to afford a back for the sofa or a horizontal position to give the required width for a bed.

One of the objects of the invention is to provide a folding sofa-bed of staunch and simplified construction which may be readily converted into a bed or folded to form a sofa, the folding and unfolding operations serving automatically to withdraw or advance to a convenient position a drawer which is concealed beneath the sofa or bed. Another object is to provide a sofa-bed equipped with track and anti-friction elements which enable the apparatus to be conveniently folded or unfolded. The sofa-bed, constructed in accordance with my invention, requires very slight wall-clearance and the folding and unfolding operations may take place with the stationary supporting structure substantially against a wall. Other objects and advantages will appear as the specification proceeds.

The invention is fully described in the following specification and shown in the accompanying drawings, in which—

Figure 1 is a sectional view in elevation, the section being taken as indicated at line 1 of Fig. 3; Fig. 2, a similar sectional view, the back and seat frame members having been swung to a different position; Fig. 3, a broken sectional view, the section being taken as indicated at line 3 of Fig. 1; Fig. 4, a perspective view of the apparatus, in unfolded position, forming a bed; Fig. 5, an enlarged detail view of the hinge and locking members; Fig. 6, a view similar to Fig. 5, showing the locking members in a different position; and Fig. 7, an enlarged view of the hinge and locking members, showing the position of these members when the apparatus is in down position, forming a bed.

In the illustration given, A represents a stationary frame support; B, a frame member constituting the seat of the sofa; and C, a frame member, hingedly connected to the member B and constituting the back of the sofa.

The supporting structure A may be of any suitable construction. In the illustration given, it is shown provided with legs A' and with arm supports A².

Fixedly secured to the frame structure A, is an inner frame comprising a pair of side rails 1 which are connected at their rear sides by back rail 2. At their front the rails 1 are secured by an inner-rail 3 which is secured to the underside of the rails 1. Any suitable means may be employed for securing the rails which constitute the inner frame to the supporting structure A.

As shown more clearly in Figs. 1, 2 and 3, the side rails 1 are equipped with track members or guides 4 which extend substantially throughout the length of the side rails 1. The track 4 may be of any suitable construction. Preferably it is formed of metal and is provided on its inner side with an opening through which connections with anti-friction elements may extend. The side rails 1 are also provided with bracket plates 5 to which are pivotally secured lateral link members 6. The links 6 are pivotally secured at their other ends to bracket plates 7 which are carried by the sides of the sofa-back C. Preferably the back C is provided with a rounded extension 8 upon which the bracket plates 7 are secured.

The seat-member B may be of any suitable construction. In the illustration given it is provided with a side rail 9 which is preferably bevelled or inclined downwardly along its front sides 10. A cross rail 11 may be used to connect the rear portions of said sides 9 and a depending wall strip 12 may be used to secure together the front sides of side strips 9. An intermediate bracing cross-piece 13 may be employed. As illustrated more clearly in Fig. 4, the depending wall 12 at the front of the seat-member B is provided with legs 14. The legs 14 may be of any suitable number or type.

The sofa-back C may also be of any desired construction. Preferably it is provided with side rails 15 which are secured together by a pair of longitudinal rails 16. As shown more clearly in Fig. 4, a pair of cross-pieces of brace-members 17 may be used

80

to connect the rails 16 at intermediate points.

The adjacent ends of side rails 9 and 15 of the frame members B and C, on each side of the sofa-bed, are each equipped with templets or hinged plates 18 and 19, respectively. The hinged plates are provided with right-angle flanges 20 which engage the top and end walls of the side rails 9 and 15 and are secured thereto by screws or other suitable means. Each hinge plate 19, carried by rail 15, is provided with a staple or U-shaped locking bar 21. Each hinge plate 18, carried by said rail 9, is equipped with a pawl 22 which is secured to the plate 18 by pivot 23. The pawl 22 is provided at its forward end with a notch or recess 24 adapted to receive the lower portion of the locking bar 21.

Pivotedly secured to the pawls 22, adjacent to the recesses 24, at points 25, are small links or dogs 26, provided at their free ends, on their under edges with notches 27 affording engaging shoulders 28.

Each of the hinged plates 18 and 19 is equipped with flange extensions 29 and 30 which overlap and are secured together by pivot 31. The pivot 31 also extends through a metal post or standard 32. Secured to the lower portion of each of the posts 32 is a foot plate 33 which carries a pair of rollers 34 pivotally secured to the plate. As shown more clearly in Fig. 3, the rollers 34 travel within the track members 4 and their pivot connections extend through the inner opening of the track members.

Secured to each of the foot plates 33 and extending inwardly therefrom are pins 35. The pins 35 are fixedly secured to the plates 33.

An open drawer 36 is supported below the frame members B and C. It may be of any suitable construction. In the illustration given, the drawer is provided with front, rear, side, and bottom walls.

The side walls 37 are provided with relatively long slots 38 which extend to the rear side of the drawer. The slots 38 are adapted to receive the pins 35 which are carried by the foot plates 33. In assembling the drawer with the moving parts of the sofa, the pins 33 enter the slots at the rear of the drawer and advance through the slots as the drawer is pushed inwardly. To prevent the pins 35 from leaving the slots 38, a removable key or locking-pin 39 is dropped through a hole which extends from the top of the drawer side and passes through the slotway 38. With the apparatus assembled as described, the forward end of drawer 36 rests upon the cross rail 3 which is secured to the fixed standard rail 1. The rear end of the drawer 36 is supported by the pins. The pins 35 are carried by the foot plates 33 which are supported by rollers 34 within the track members 4. Likewise, the hinged ends of the side rails 9

and 15 are supported by posts 32 which rest upon foot plates 33.

In the operation of the apparatus, Fig. 1 illustrates the apparatus in its folded position in which it serves as a sofa. The locking bar is shown in engagement with the notch or recess 24 of the pawl 22. The slightly inclined angle of the sofa-back C maintains the parts in this position. When it is desired to convert the sofa into a bed, the front end of the seat member B is raised to the position illustrated in Fig. 2, the track elements cooperating with the link 6 to carry the hinged parts of members B and C to a forward position. As will be observed in Fig. 2, the notch 27 of the dog 26 is still held out of engagement with locking bar 21. In order to release the locking mechanism, the seat member B is tilted slightly rearwardly thus bringing the notch 27 of dog 26 into alignment with the bar 21. The dog 26 drops into lowered position with the shoulder 28 engaging bar 21. When the seat member B is now lowered, the dog 26 swings about its pivot 25 and carries the recess 24 of pawl 22 out of engagement with the bar 21. The pawl 22 then slides forwardly within the U-shaped locking bar 21 as the seat-member B drops to a horizontal position, as illustrated more clearly in Figs. 4 and 7.

As the foot plate 33 moves forward with the hinged members 18 and 19, the pin 35 engages the drawer at the forward end of the slot and moves the drawer forward to assume the position shown in Fig. 2. When the seat-member B is dropped to horizontal position, as shown in Fig. 4, the extended drawer is concealed by the front wall 12 of seat B. When it is desired to have access to the drawer, the front end of seat member B may be raised to the angular position desired. In returning the members to their original position, to form the sofa, the hinged portions of the drawer, carried by the cooperating rollers and track members, are moved rearwardly and the back C, guided by link members 6, is brought to a vertical position. The retraction of the foot plate 33 causes the pin 35 to engage key 39 and in this manner the drawer 36 is automatically withdrawn to a position below the member B, which now forms the seat of the sofa. The notch 27 of dog 26 is held out of engagement with the bar 21 and the bar 21 is held in engagement with the notch 24 of pawl 22 by the slight tilting of the back C.

If desired, the apparatus may be converted from bed-form to sofa-form by first raising the seat B to the position illustrated in Fig. 2, the recess 24 of pawl 22 being brought into engagement with bar 21. The seat B may then be lowered and the back C raised while, at the same time, the hinged portions of the members are moved rearwardly upon the supporting anti-friction elements. The with-

drawal of the foot plate 33 brings pin 35 into contact with key 39 and simultaneously withdraws the drawer 36 within the base part of the sofa-bed.

5 With the apparatus illustrated, it will be observed that the drawer is automatically extended or retracted during the sliding movement of the hinged frame members and is concealed both in its retracted 10 or extended position by the depending front wall 12 of the frame member B.

If it is desired to remove the drawer entirely this may be readily accomplished by lifting the key 39 out of the slotway 38 and 15 then withdrawing the drawer.

The foregoing detailed description has been given for clearness of understanding only and no unnecessary limitations should be understood therefrom, but the appended 20 claims should be construed as broadly as permissible in view of the prior art.

I claim:

1. In a sofa-bed, a stationary supporting structure, hingedly connected frames carried thereby, said frames constituting respectively a sofa-seat and a sofa-back, means on the connected frames coacting with means on the stationary supporting structure for slidably supporting said frames upon said 30 supporting structure, a drawer slidably mounted in said structure, said drawer being provided at its sides with a slot-way, and a pin carried by said first-mentioned means and engaging a slotway of said drawer.

35 2. In a sofa-bed, a supporting structure, hingedly connected frames carried thereby, said frames constituting respectively a sofa-seat and a sofa-back, track members carried by said supporting structure, anti-friction 40 elements disposed therein, supporting posts connected to said anti-friction elements and slidably carrying said frames, a drawer slidably mounted in said supporting structure and having a side provided with a slot-way, and a projection carried by a supporting 45 post and engaging said slot-way.

3. In a sofa-bed, a supporting structure, hingedly connected frames constituting respectively a sofa-seat and a sofa-back, a supporting member slidably carrying the hinged portion of said frames upon said supporting structure, a drawer slidably engaging said supporting structure and having a side provided with a slot-way, and a projection carried by said supporting member and engaging the slot-way of said drawer.

4. In a sofa-bed, a supporting structure, hingedly connected frames carried thereby 50 and constituting respectively a sofa-seat and a sofa-back, a supporting member slidably engaging the supporting structure and carrying said frame members, a drawer having its rear end portion adjustably carried by 55 said supporting member and slidably engag-

ing the front portion of said supporting structure.

5. In a sofa-bed, a supporting structure, hingedly connected frames constituting respectively the sofa-seat and the sofa-back, a supporting member slidably engaging said supporting structure and carrying said frames, a drawer slidably mounted in said supporting structure and having an open slot-way extending from its rear end forwardly, 75 and a projection carried by said supporting member and engaging said slot-way.

6. In a sofa-bed, a supporting structure, hingedly connected frames constituting respectively the sofa-seat and the sofa-back, supporting members slidably mounted in said supporting structure and carrying the hinged portions of said frames, a drawer slidably mounted in said supporting structure and having its sides provided with open slot-ways 80 extending from the rear end forwardly, pins carried by said supporting members and engaging said slot-ways, and retaining pins extending through the sides and slot-ways of said drawer and at right angles to said 85 slot-ways.

7. In a sofa-bed, a stationary supporting structure, a pair of frames constituting respectively a sofa-seat and a sofa-back, said frames being hingedly connected, means on the connected frames coacting with means on the stationary supporting structure for slidably supporting said frames upon said supporting structure, a drawer also slidably mounted in said supporting structure, and 100 slidable connecting means between said frames and drawer.

SOLOMON KARPEN.
